UNITED STATES PATENT OFFICE.

CHARLES STOLLBERG, OF TOLEDO, OHIO, ASSIGNOR TO AMERICAN CAN COMPANY, OF NEW YORK, N. Y., A CORPORATION OF NEW JERSEY.

SHEET-METAL LEAD-KEG.

1,198,082.

Specification of Letters Patent. Patented Sept. 12, 1916.

Application filed November 12, 1912. Serial No. 730,880.

To all whom it may concern:

Be it known that I, CHARLES STOLLBERG, a citizen of the United States, residing in Toledo, in the county of Lucas and State of Ohio, have invented a new and useful Improvement in Sheet-Metal Lead-Kegs, of which the following is a specification.

This invention relates to improvements in sheet metal kegs such as are commonly used 10 for transporting white lead.

An object of the invention is to provide a keg having a seamless drawn body member provided with a strengthening or reinforcing bead or rim at the top or mouth end, the 15 bead or rim serving also as a shoulder to which the cover can be clamped, said body being additionally reinforced at the bottom portion by means of a strengthening or reinforcing band, preferably electrically spot 20 welded to the body, said strengthening band being also provided with a bead or rim corresponding in outside diameter to the outside diameter of the bead or rim at the top end of the keg, whereby the keg may be 25 easily rolled in a straight line.

The invention furthermore consists in the improvements in the parts and devices and in the novel combinations of the parts and devices herein shown, described or claimed.

30 In the drawing forming a part of this specification, Figure 1 is a longitudinal, sectional view of a lead keg and cover therefor embodying my improvements, and Fig. 2 is a transverse, sectional view taken substantially on the line 2—2 of Fig. 1.

In the drawing, the main or body portion 35 of the keg is represented by the numeral 10, and as shown, the same is drawn seamless and at its upper end or mouth portion is 40 provided with the usual form of strengthening or reinforcing bead or rim 11 over which is adapted to fit the curved flange 12 of a countersunk cover 13, said rim being 45 provided at intervals with fastening lips or projections 14 adapted to be bent around and under the bead or rim 11. The body member 10, is necked in at the bottom thereof, as shown at 15, thereby providing the body 50 with a shoulder 16. Rigidly secured to the necked-in portion 15, and preferably by spot

welding, is a reinforcing band or strip 17, the latter being provided at its lower edge with a bead or rim 18, similar to the bead or rim 11 and of substantially the same diameter from outside edge to outside edge. 55

From the foregoing description it will be seen that the lead keg is reinforced at the bottom substantially as strongly as at the top and that the shoulder 16 serves as an abutment for the band 17 when the keg is 60 placed on end, and that by making the beads or rims 11 and 18 of the same diameter, the kegs may be easily rolled in a straight line, thereby overcoming a defect commonly found in lead kegs as hitherto manufactured, 65 wherein the diameter of the keg at the mouth end has been considerably greater than that at the bottom, thus preventing the kegs from rolling in straight lines.

I claim:—

1. A sheet metal lead keg of the character described comprising, in combination: a drawn, seamless body member having an integral bottom and provided with a strengthening bead at its top end, said body 70 being necked-in at the bottom thereof; and a strengthening band permanently secured to the body member around the necked-in portion thereof, said strengthening band being provided with a bead of substantially 75 the same diameter as the bead at the top end of the keg, whereby the keg is adapted to be rolled in a straight line.

2. A sheet metal lead keg of the character described, comprising, in combination: a drawn, seamless body member having an integral bottom and provided with a strengthening bead at its top end, said body 85 being necked-in at the bottom thereof; and a strengthening band welded to the body 90 member around the necked-in portion thereof, said strengthening band being provided with a bead of substantially the same diameter as the bead at the top end of the keg, 95 whereby the key is adapted to be rolled in a straight line, substantially as specified.

CHARLES STOLLBERG.
